United States Patent Office.

JAMES MONTGOMERY, OF NEW YORK, N. Y.

Letters Patent No. 91,656, dated June 22, 1869; antedated June 18, 1869.

IMPROVED MACHINE-BELTING.

The Schedule referred to in these Letters Patent and making part of the same.

To all whom it may concern:

Be it known that I, JAMES MONTGOMERY, of the city, county, and State of New York, have invented certain new and useful Improvements in Machine-Belting; and I do hereby declare that the following is a sufficiently full, clear, and exact description thereof, to enable one skilled in the art to which my said invention appertains to make and carry it into effect, reference being had to the accompanying drawings, which are made a part of this specification.

The object of my invention is to construct leather belting for driving machinery, that without increase of cost, additional strength may be imparted to the edges of the belt where it is most liable to wear and break; and, further, in the employment or use of means for connecting the parts of the belt, which will involve less cutting away of material, and consequent weakening, than fastenings in common use.

In the drawings—

Figure 1 represents a plan of a piece of quadruple belting illustrating my invention.

Figure 2 shows a longitudinal section of the same at *x x*, fig. 1.

Figure 3 is a plan view of a piece of single belting, with edges turned down and secured by stitching.

Figure 4 shows a longitudinal section thereof at *y y*, fig. 3.

Figure 5 is a plan view of my improved single belting without stitching.

Figure 6 represents a transverse section of the same at *z z*, fig. 5.

In carrying out my invention, I form on the leather, or other material, bevel or feather-edges *a a*, and turn these down, so that no raw or single edge will exist on the finished belt.

The turning and pressing down of the edges may be effected by passing the belt between suitable rollers, presses, or dies, provided with circumferential grooves, corresponding in size and shape with the finished belt which is to be produced.

For securing the tapered and turned edges, I employ water-proof cement, or stitching, or rivets, or any other suitable means of fastening.

At the ends where it is necessary to punch holes for the reception of lacings, or other means of connection, I fold transversely, as shown at *b*, in Figure 7, so as to impart additional thickness so far in excess of the amount of material necessarily cut away in punching the holes *c c* that no weakening occurs at these points.

Belts of any required strength may be produced by folding one thickness within another, as clearly shown in fig. 1, the edges of the respective leaves or sheets being brought together and lapped in the centre, and secured by a single row of stitching through the whole.

In making triple belts, the inner or centre piece may be inserted in single flat form, but I prefer to turn up the edges of this also.

The advantages of this improvement are various. Among others, the lateral strain, occurring alternately, first on one side and next on the other, thereby enormously increases the strain on that side of the belt.

It is met by presenting the additional strength due to turning the leather down, as shown, instead of cutting the material in layers, thereby presenting the raw edges of the leather, as also the cement lying between the same, whereby, being exposed to wet or moisture, the belt is rapidly destroyed by the solvent action of such moisture; the raw edges of the leather will be far more readily torn and disrupted than the improved edge made known within.

Having thus described my invention, the following is what I claim as new, and desire to secure by Letters Patent:

1. I claim constructing leather belting for machinery with folded edges, substantially as and for the purposes set forth.

2. I further claim thickening the ends of the belting, to compensate for material punched out to receive the lacings, or other fastenings.

JAMES MONTGOMERY.
